Specification for Design.

Patented Mar. 9, 1920.

Application filed August 29, 1919. Serial No. 320,742. Term of patent 14 years.

To all whom it may concern:

Be it known that we, LE BARON KINNEY, a citizen of New Brunswick, Canada, and CHARLES R. DUFFIN, a citizen of the United States, and both residents of the city of Terre Haute, in the county of Vigo and State of Indiana, have jointly invented a new, original, and ornamental Design for a Spring-Shackle Perch for Ford Automobiles, of which the following is a specification, reference being had to the accompanying drawings, forming part hereof, in which—

Figure 1, is a view of the side of the spring-shackle perch.

Fig. 2, is a view of one edge of the spring-shackle perch, taken from the rear.

We claim:—

The ornamental design for a spring-shackle perch, as shown.

LE BARRON KINNEY.
CHARLES R. DUFFIN.
